(57) **CLAIM**

The ornamental design for a pocketed luggage cover, as shown and described.

DESCRIPTION

FIG. 1 is a front perspective view illustrating our design for a pocketed luggage cover.

FIG. 2 is a rear perspective view thereof.

FIG. 3 is a front view thereof.

FIG. 4 is a right side view thereof.

FIG. 5 is a rear view thereof.

FIG. 6 is a left side view thereof.

FIG. 7 is a top view thereof.

FIG. 8 is a bottom view thereof.

FIG. 9 is another rear view thereof, with an extended luggage handle, represented in broken lines, and a beverage cup with a straw, a beverage bottle and a magazine, each also represented in broken lines, placed in pockets of the pocketed luggage cover; and,

FIG. 10 is another front view thereof, with the extended luggage handle, represented in broken lines, and a beverage cup with a straw, a beverage bottle and another magazine, each also represented in broken lines, placed in pockets of the pocketed luggage cover.

The broken lines shown in FIGS. 1 through 10 representing a piece of luggage, including the luggage handle, are environmental and form no part of the claimed design. The additional broken lines in FIGS. 9 and 10 representing items in pockets are also environmental and form no part of the claimed design.
